(57) **CLAIM**

(21) Appl. No.: **29/348,188**

The ornamental design for a “absorbent cleaning device with fluid barrier”, as shown.

(22) Filed: **Dec. 7, 2009**

DESCRIPTION

(51) **LOC (9) Cl.** 04-01

FIG. 1 is a perspective view of a absorbent cleaning device with fluid barrier showing my new design;

(52) **U.S. Cl.** D32/40

FIG. 2 is front elevational view thereof;

(58) **Field of Classification Search** D32/40, D32/50; 15/104.93, 109.94, 208, 209.1, 15/228, 231, 233; 442/381; D5/57

FIG. 3 is rear elevational view thereof;

See application file for complete search history.

FIG. 4 is a left side elevational view thereof;

(56) **References Cited**

FIG. 5 is a right side elevational view thereof;

U.S. PATENT DOCUMENTS

FIG. 6 is a top plan view thereof;
